US00D822713S

(12) **United States Design Patent** (10) Patent No.: **US D822,713 S**
Chaudhri et al. (45) Date of Patent: ** Jul. 10, 2018

(54) **DISPLAY SCREEN OR PORTION THEREOF
WITH GRAPHICAL USER INTERFACE**

(71) Applicant: **Apple Inc.**, Cupertino, CA (US)

(72) Inventors: **Imran Chaudhri**, San Francisco, CA (US); **Joe Marianek**, San Francisco, CA (US); **Christopher Daryl Soli**, Mountain View, CA (US); **Christopher Wilson**, San Francisco, CA (US); **Eric Lance Wilson**, San Jose, CA (US)

(73) Assignee: **Apple Inc.**, Cupertino, CA (US)

(**) Term: **15 Years**

(21) Appl. No.: **29/619,456**

(22) Filed: **Sep. 29, 2017**

Related U.S. Application Data

(63) Continuation of application No. 29/563,422, filed on May 4, 2016, now abandoned, which is a continuation of application No. 29/523,055, filed on Apr. 6, 2015, now Pat. No. Des. 756,396, which is a continuation of application No. 29/457,315, filed on Jun. 9, 2013, now Pat. No. Des. 726,219.

(57) **CLAIM**

The ornamental design for a display screen or portion thereof with graphical user interface, as shown and described.

DESCRIPTION

The FIGURE is a front view of a display screen or portion thereof with graphical user interface showing the claimed design.

The broken lines in the FIGURE show a display screen or portion thereof, and form no part of the claimed design.

1 Claim, 1 Drawing Sheet
